THREAD AND CORD TRIMMER FOR BUTTON-HOLE SEWING MACHINES

Edward P. Spaine, Bridgeport, and Harold C. Faulkner, Long Hill, Conn., assignors to The Singer Manufacturing Company, Elizabeth, N. J., a corporation of New Jersey

Application September 8, 1938, Serial No. 228,912

25 Claims. (Cl. 112—252)

This invention relates to buttonhole sewing machines of the 'eyelet-end' type having stitch-forming mechanism and a work-clamp which are relatively rotatable about an axis normal to the plane of the work to place the stitches radially about one end, usually the eyelet-end, of a buttonhole. These machines sew with an upper or needle-thread and an under or looper-thread and they commonly embody means to lead 5 a comparatively heavy under thread or stay cord within the range of the stitch-forming mechanism, so that such cord will be bound around the buttonhole by the usual buttonhole overseaming stitches which are formed by the needle 10 and looper about the cord. The machines also commonly embody buttonhole-cutting mechanism which, in some cases, is caused to operate after the sewing operation to cut the buttonhole slit after the buttonhole is stitched and, 15 in other cases, is operated prior to the sewing operation to cut the button-hole slit before the sewing operation is commenced. These latter machines are known as 'cut-first' machines and are used to sew high grade buttonholes in clothing materials having sufficient body or tightness 20 of texture to prevent fraying of the threads of the material at the buttonhole slit during the buttonhole sewing operation.

It is customary in sewing cut-first buttonholes 25 in clothing materials to pass from one buttonhole to the next without cutting the stay cord or the needle and looper-threads, so that the buttonholes of a given series on a garment are connected by the cord and threads common to the series. The cord and threads are subsequently 30 cut by hand so that free ends of cord and thread are provided at the finishing end of the buttonhole. These free cord and thread ends are demanded by the trade in a high grade machine-made buttonhole in order that the cord and thread ends may be of sufficient length to be 35 twisted together or drawn through the buttonhole slit prior to the bar-tacking operation performed by another machine to finish the buttonhole. After the bar-tacking operation, which effectively ties down and anchors the threads and cord, the projecting free ends of the threads and cord are cut off by hand close to the finishing 40 bar stitches.

In following this known and customary procedure, there is considerable wastage of cord and thread, usually of expensive grades, as the long connecting portions of cord and thread between adjacent buttonholes are cut off and thrown away. Also, time is lost in shifting the work in

the work-clamp of the buttonhole sewing machine due to pull on the cord and threads which tends to distort the buttonhole unless the work is carefully shifted.

An object of the present invention is to provide a buttonhole sewing machine with trimming means for both the needle and looper-thread, as well as the cord, which will trim the under thread, including the cord, at a distance from the finishing end of the buttonhole, 5 so as to leave cord and looper-thread ends of sufficient length for the bar-tacking operation. Another object of the invention is to provide for the correct aligning or positioning of the beginning cord and looper-thread ends, after the trimming operation, to insure that the cord will be covered by the initial stitches of the next sewing operation and that the first looper-thread loop 10 will be properly positioned for seizure by the auxiliary looper or detainer of the under-thread mechanism. Another object of the invention is to provide an automatic buttonhole sewing machine with a work-clamp constructed to clamp the work at all points along the sides of the buttonhole slit position and with means to trim the 15 cord and thread ends long enough for the usual bar-tacking operation performed by another machine. A further object of the invention is to provide means to cut the needle-thread previous to the cutting of the looper-thread and cord, to 20 eliminate the waste loop of needle-thread heretofore left on one of the lower loop-retainers of the under thread mechanism, necessitating the provision of a waste loop gripper for the removal of the waste loop. The invention also 25 aims to provide the machine with a work-clamp releasing and unspreading mechanism which is 30 timed to operate after all other operations of the machine including the thread and cord trimming operation, have been completed.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

Fig. 1 is a right side elevation of a buttonhole 50 sewing machine embodying the invention. Fig. 1^a is a plan view of a stitched buttonhole as produced by the machine. Fig. 2 is a left side elevation of the machine. Fig. 2^a is a detail plan view, partly in section, of the looper-thread ten- 55

- sion-release mechanism. Fig. 2^b is a rear end elevation of the parts shown in Fig. 2^a. Fig. 3 is a bottom plan view of the machine. Fig. 4 is a front end elevation of the machine, partly in section. Figs. 5 and 6 are plan views of the work-clamp on the bed of the machine; the work-clamp being shown unspread in Fig. 5 and spread in Fig. 6. Figs. 7 and 8 are side elevations of the work-clamp; the clamp being shown 10 closed in Fig. 7 and open in Fig. 8. Fig. 9 is a right side elevation of the turret of the stitch-forming mechanism and the associated parts of the needle-throat-tipping mechanism of the machine.
15. Fig. 10 is a disassembled perspective view of the tipping needle-throat supporting frame and locking device therefor. Fig. 11 is a left side elevation of the turret shown in Fig. 9, showing the parts for operating the locking device for 20 the tipping needle-throat. Fig. 12 is a similar view showing the needle-throat carrying frame unlocked just prior to the needle-throat tipping operation. Fig. 13 is a side elevation of the needle-thread cutting lever on the turret and the 25 operating means therefor. Fig. 13^a is a right side elevation of the parts shown in Fig. 13. Fig. 14 is a top plan view of the turret and associated parts shown in Fig. 9. Fig. 15 is a top plan view of the turret as it is beginning its reverse rotation at the end of the second side stitching operation on the buttonhole. It is early in the reverse rotation of the turret that the needle-thread cutter is operated as shown in Figs. 13 and 15 to cut the needle-thread below the work.
- 30 Fig. 16 is a view similar to Fig. 15 but at a slightly later stage in the reverse rotation of the turret or after the needle-thread has been cut. Fig. 17 is a view of the needle-thread cutter at the position shown in Fig. 15 which is at the 35 time of cutting of the needle-thread loop on the looper. Fig. 18 is a top plan view of the turret and associated parts after the reverse rotation of the turret has been completed and the needle-throat member has been tipped forwardly to 40 provide space for the operation of the thread and cord trimmer which is advancing to cut the looper-thread and cord. Fig. 19 is a left side elevation of the parts shown in Fig. 18.
- 45 Fig. 20 is a view similar to Fig. 19 but showing the cord and looper-thread severed. Fig. 20^a is a view similar to Fig. 20 but with the needle-throat member restored to vertical position. Fig. 21 is a plan view of the needle-throat member and a special tongue on one of the work-clamping plates at the position shown in Fig. 20. Fig. 50 22 is a view similar to Fig. 21 but with the needle-throat member moving back to its initial upright position. Fig. 23 is a similar view with the needle-throat member restored to its initial position. Fig. 24 is an elevation of the stitch-forming instrumentalities showing the threaded looper taking the first needle-thread loop and presenting the first looper-thread loop to one of the loop-detainers. Fig. 25 is an inside view of 55 the pattern wheel and associated parts of the rapid-feed control mechanism. Fig. 26 is a sectional view substantially on the line 26—26, Fig. 3, showing the rapid-feed clutch-operating mechanism. Fig. 27 is a side elevation of the 60 cord pull-off device showing how slack cord is provided for the eyelet-end sewing operation. Fig. 28 is a similar view showing how an increased amount of slack cord is provided for the 70 thread and cord trimming operation. Fig. 29 is a detail elevation, partly in section, of the nee-

dle-thread pull-off and nipper. Fig. 30 is a section through the upper collar-element of the thread-nipper. Fig. 31 is a top plan view of the needle-throat member and Fig. 32 is a section on the line 32—32, Fig. 31.

5 The machine is constructed with a frame including the hollow box-like bed 1 from which rises the standard 2 of the overhanging goose-neck 3 terminating in the head 4. The stitch-forming mechanism is constructed substantially 10 in accordance with the disclosure of the Allen et al. Patent No. 1,372,473, dated Mar. 22, 1921. It comprises the upper endwise reciprocatory and laterally vibratory needle 5 and the lower threaded and non-threaded loopers, 6 and 7, respectively, with their complementary loop-retainers 8 and 9, respectively. The loopers and loop-retainers are carried by the turret 10 which, together with the needle 5, is turned about a vertical axis to place the stitches radially about the eyelet-end of a buttonhole and is reversely turned at the completion of the buttonhole sewing period to restore the stitch-forming implements to their initial positions. The means to so rotate the stitch-forming devices comprise the usual upper and under sector gears 11 and 12 and their connections with the vertical shaft 13 to which is fixed the lever-arm 14 having a cam-follower roll 15 entering the stitch-rotating cam-groove 16 in the feed-wheel 17. The stitch-forming devices are driven by the main sewing shaft 18, the period of operation of which is controlled by the stop-motion device 8 which includes the usual tilting stop-motion lever 19 fixed to the rock-shaft 20 to which is fixed an arm 21 connected by the link 22 to the lever 23 fulcrumed on the bed 1 at 24 and carrying a follower nose 25 in position to be engaged by the 'start-sewing' cam-incline 26 on the pattern wheel 27 fixed to the cross rotary shaft 28 which is geared to and runs one-to-one with the feed wheel 17. The pattern wheel is also formed with a 'stop-sewing' drop-off shoulder 29.

40 The laterally vibratory needle 5 works through the laterally elongated sewing aperture 30 in the button-like needle-throat member 31 which has the usual hole 32 to guide the gimp or stay cord c to a position within the range of the needle 5. The needle-throat member 31 has at one side of the usual cord guide hole 32 another cord guide hole 32' in an edge-tongue 32'' specially provided in the present instance to prevent the cord from dropping into the paths of any of the under thread handling implements or from fouling itself on the needle-thread cutting blade in the restoration of the needle-throat member to vertical position after having been tipped. The additional passageway 32' at an angle to the conventional passageway 32 also is a help in preventing back motion of the cord end in the needle-throat member after the cord is cut and during the return of the needle-throat member to vertical position. Instead of being fixed immovably to a post on the turret, as heretofore, the needle-throat member is now mounted on a yoke 33, Fig. 65 10, which is pivoted on the aligned pins 34 carried by the turret posts 35. While the needle-throat member may be tipped or tilted about the axis of the pins 34 during the thread and cord trimming operation, as shown in Fig. 19, it is locked in 70 a definite upright position, Fig. 9, throughout the sewing operation. The locking means comprises a latch-arm 35' which hooks over the arm extension 36' of the yoke 33. The latch-arm 35' is fixed to one end of the rock-shaft 37' journaled

in bearings 37, Fig. 15, on the turret 10. The rock-shaft 37 is biased by the coil-spring 38 to urge the latch arm 35 to yoke-locking position. In the locked position of the yoke 33, the abutment screw 39 carried thereby engages one of the turret posts 35, as shown in Fig. 14.

The needle-throat tipping mechanism comprises the roller stud 36 on the yoke 33, which stud in the initial position of the turret 10 is received in the horizontal slot 31 in the lever 38 fulcrumed on the pin 39 carried by the post 40 on the bed-frame 1. The lever 38 carries a ball-stud 41, Figs. 9 and 14, which enters a slot 42 in the arm 43 of a lever fulcrumed at 44 on the bed 1 and having another arm 45 which carries a follower roll 46 entering the needle-throat-tipping cam-groove 47 in the inner face of the gear-wheel 48 which is fixed to the cross rotary shaft 28.

20 The rock-shaft 37 which at one end carries the needle-throat latch 35 has fixed to its opposite end an arm 49, Figs. 10 and 12, to which is pivoted at 50, the spring-biased follower element 51; the spring biasing this element 51 against the stop-pin 52. At the end of a sewing operation when the turret 10 is given its reverse rotation the element 51 is, near the close of said reverse rotation, caused to ride up the incline 53 of a stationary cam-block 54 adjacent the turret 10 and unlock the needle-throat carrying yoke 33. As soon as said yoke is unlocked and before the reverse rotation of the turret 10 is completed, the slightly eccentric portion 55, Fig. 9, of the cam-slot 47 imparts a slight tipping movement to the yoke 33 sufficient to raise the arm 36, Fig. 12, high enough to prevent reengagement of the latch 35 thereover when the follower element 51 drops off of the end of the cam-block 54 at the close of the reverse rotation of the turret 10. The needle-throat tipping yoke 33 is thus unlocked by the final reverse rotation of the turret 10 at the close of a sewing period and is ready to be fully tipped for the thread and cord severing operation to be described.

45 The work-clamp comprises the usual lower work-supporting plates 56 and upper clamping feet 57 carried by the arms 58 fulcrumed at 59, Figs. 7 and 8, on the respective lower plates 56. The clamps are closed by the cams 60 on the usual connected rock-shaft sections 61 one of which carries a clamp-closing finger-piece 62 and a rearwardly extending arm 63 in position to be engaged by the usual clamp-closing lever 64 which is fulcrumed at 65 on the standard 2 and is actuated at the beginning of a buttonhole producing cycle by mechanism constructed substantially in accordance with the disclosure of U. S. Patent No. 1,832,665, dated Nov. 17, 1931. When the clamps are closed they are held closed by engagement of the spring-biased latch-arm 66 with the arm 67 on the rock-shaft section 61 shown in Fig. 7. The latch-arm 66 is fixed to a rock-shaft 68 journaled in the bracket 69 fixed to one of the work-clamp fulcrum-blocks 10. The rock-shaft 68 has fixed to its outer end a cylindrical head 71 diametrically slotted to receive an arm 72 which is fulcrumed at 73 in said head and is biased by the spring 74 to the vertical position shown in Figs. 4, 7 and 8. This arm 72 is engaged at the end of a buttonhole producing cycle by the clamp-opening and unspreading mechanism to be described.

The lower clamp-plates are mounted as usual for spreading movements upon the cross slide plate 75 which is carried by the usual longitudi-

nal slide frame 16. The clamp-spreading movements are imparted to the clamp-plates by the usual toggle mechanism, such as disclosed in U. S. Patent No. 15,324; reissued Apr. 4, 1922. This toggle mechanism includes a central lever 77 fulcrumed at 78 on the cross slide plate 75 and two toggle links 79, 80 pivoted at 81, 82, respectively, to the lateral slide plates 82', 82'' engaged by the lower clamp-plates 56. The toggle spreading and unspreading lever 83 is fulcrumed at 84 on the lateral slide plate 82'' and has a forked end which embraces a stud 85 on the central lever 77. The work-clamps are shown spread in Fig. 6 and unspread in Fig. 5. Pivotally connected to the lever 83 at 86 is a link 87, Fig. 6, 15 which is pivotally connected at its front end at 88 to a lever 89 fulcrumed at 90 on the under side of the cross slide plate 75. This lever 89 engages the hooked end of a slide-bar 91 carrying wedges 92, Fig. 3 which are engaged by 20 blocks 93 on the levers 94 fulcrumed at 95 on the cross slide plate 75. The levers 94 are apertured at their forward free ends to receive the pins 96 which project downwardly from the inner forward corners of the lower clamp-plates. 25 When the lever 83 is shifted from the position shown in Fig. 5 to that shown in Fig. 6, to spread the toggle mechanism connected to the rear ends of the lower clamp-plates 56, the link 87 connected to the lever 83 causes the lever 89 30 and slide-bar 91 carrying the wedges 92 to be operated to spread the forward ends of the lower clamp-plates 56

In a buttonhole producing cycle, the work-clamps are first rapidly moved over the bed 1 35 to carry the work from buttonhole cutting position to sewing position and then, more slowly, to place the stitches about the buttonhole and then rapidly from sewing position back to buttonhole cutting position. The movements are effected 40 by the usual feed-lever connections with feed-cam grooves in the feed-wheel 17. These feed-lever connections and feed-actuating means are constructed substantially in accordance with the disclosure in said reissued Patent No. 15,324. 45

The rapid feed of the work-clamp from buttonhole cutting position to sewing position and return is effected by the usual constantly running rapid-feed drive shaft 93', which through a worm and gear reduction 94', Fig. 3, drives the live element 95' of a clutch, the driven element 96' of which is fast on the cross rotary shaft 28. It will be understood by referring to said U. S. reissued Patent No. 15,324 that the withdrawal of the cone 97 from the driven clutch-element 96' effects engagement of the driving and driven clutch-elements 95', 96', while projection of the cone 97 toward the driven clutch-element 96' effects declutching of the parts 95', 96'. The cone 97 is operated by the usual arm 98 rigidly mounted on the cross slide-rod 99 and carrying the lateral pin 100 and latching block 101, Fig. 26. 50 55 60

As disclosed in U. S. Patent No. 1,548,815, Aug. 11, 1925, there is mounted in the base 1 on the bracket 102, Fig. 26, a continuously rocking bell-crank lever 103, 104, the forked arm 103 of which embraces a crank 105 on the rapid-feed drive shaft 93'. Pivoted on the arm 104 is a single reciprocating bar 106 the free end of which has connected to it a spring 106' which pulls the bar 70 upwardly against the seat 107 of the latch 108 pivoted at 109 on the bed 1. The bar 106 reciprocates idly when held down by the latch 108. When the latch 108 is shifted to release the bar 106, the latter is drawn upwardly by the spring 75 75

106' and the shoulder 110, Fig. 26, engages the pin 100 and pushes the slide-rod 99 to the right against the resistance of the recovery spring 111 to withdraw the cone 97 from the clutch-element 96' and effect the coupling of the rapid feed shaft 93' to the cross rotary shaft 28 to drive the feed-wheel 17 at its rapid rate. When the slide-rod 99 is pushed to clutch-engaging position, it is held there by engagement of the shoulder 112 on the lever 113 with the latch block 101; the lever 113 being biased upwardly about its fulcrum 114 by the spring 115. Thus, the lever 113 and shoulder 112 act as a spring latch to hold the slide-rod 99 in rapid-feed position. During the return movement of the push-bar 106 the inclined shoulder 116 thereon engages the pin 100 and causes the push-bar to be depressed sufficiently to be re-engaged in idling position by the latch-lever 108.

20 The pattern wheel 27 on the cross rotary shaft 28 has on its inner face two tripping points 117 which tilt the lever 118 whose forked end 119 embraces the rapid-feed throw-out latch lever 113. These tripping points control the throwing 25 out of the rapid feed first, as the sewing starts and last, at the completion of a buttonhole-producing cycle.

The controlling means for initiating the rapid feed prior and subsequent to the sewing period 30 are substantially the same as those disclosed in U. S. Patent No. 1,548,815 and comprise the rock-shaft 120 having an arm 121 engaging the latch 108, another arm 122 adapted to be depressed by a cam 123 on the cutter-shaft clutch disk 124, 35 and a third arm 125 adapted to be elevated by the pawl 126 actuated by the stop-motion device 5.

The present machine is of the 'cut-first' type; the buttonhole cutting mechanism being constructed substantially in accordance with the disclosure of said U. S. Patent No. 1,548,815 and embodying the travelling buttonhole cutter levers 127, 128 which are given their customary travelling and closing-and-opening movements 40 by suitable cams on the buttonhole cutter shaft 129 to which a single rotation is imparted prior to sewing by the continuously running pulley 130 through a one-revolution clutch including the clutch disk 124 carrying the radially sprung- 45 pressed clutch-tooth 131. This clutch mechanism is constructed substantially in accordance with the disclosure of said U. S. Patent No. 1,548,815.

When the sewing operation is started by the 50 'start-sewing' cam incline 26 on the pattern wheel 27, the first rapid feed is thrown out and the drive of the feed-wheel 17 is effected more slowly and in step-by-step fashion by the usual pin-and-star-wheel drive 132, Figs. 1, 2 and 3, 55 through suitable gears; the main sewing shaft 18 doing the driving.

At the end of a sewing operation the needle-thread is cut by a cutting blade 133 having a 60 needle-thread-cutting knife-edge 134 and a looper-thread retaining hook 135 at opposite sides of an intervening slot. The blade 133 is mounted on an upstanding lever-arm 136 which is fulcrumed at 137 on one of the turret posts 35, as 65 shown in Fig. 13a. The lever-arm 136 is biased by the spring 138 to the vertical position, shown in Fig. 9, with the lever-arm stop-shoulder 139, Fig. 13, in contact with the head of one of the pivot-studs 34. There is pivoted on the lever-arm 136 a spring-biased follower element 140 the 70 spring-influenced motion of which about its pivot

141 is arrested by the stop-pin 142. Early in the reverse rotation of the turret 10 after a sewing period, the follower element 140 encounters the stationary block 143, Figs. 13 and 15, alongside the turret 10, and tilts the lever-arm 136 5 sufficiently to cause the knife-edge 134 to engage and sever the limb of the needle-thread loop on the detainer 9 which leads to the last stitch, Fig. 17. After the follower element 140 has passed over the stationary block 143 the lever-arm 136 10 is restored to its initial position, Fig. 16, by its biasing spring and the looper-thread is caught by the hook 135 and retained under control for a purpose to be explained. When the turret is 15 being turned (clockwise in Fig. 14) in sewing around the eyelet-end of a buttonhole, the follower element 140 is free to swing on its pivot 141 when it encounters the block 143 and brushes idly past said block 143 to a position intermediate the stationary blocks 143 and 54.

The looper-thread and cord are, in the present instance, cut by a scissors device, similar to that shown in U. S. Patent No. 1,579,200, dated April 6, 1926. Heretofore, however, the scissors device has been positioned to cut the threads and cord at a point as close as possible to the last stitch and it was necessary to cut scissors clearance slots in the lower clamp-plates to expose the under surface of the work. Scissors clearance 25 slots in the lower clamp-plates, such as heretofore provided, would interfere with the uniform clamping and spreading of the work along the buttonhole slit in a 'cut-first' machine.

For this reason and the further reason that the trade demands long cord and thread ends in cut-first buttonholes, the present scissors device has been moved forwardly (see Fig. 18) so as to operate in a path about $\frac{3}{4}$ " in advance of the last stitch in the longest buttonhole which may be made by the machine. For any shorter 40 buttonhole, the trimmed thread and cord ends will be correspondingly longer on return side of buttonhole. To avoid clashing of the scissors with the needle-throat member 31 normally positioned in this path at the end of a sewing period, 45 provision is made for tipping the needle-throat member 31 forwardly about the pivot pins 34, prior to the arrival of the scissors at cutting position. This tipping movement of the needle-throat member 31 accomplishes certain additional desirable functions. For example, the member 31 is moved forwardly and downwardly in the arc of a circle and causes the looper-thread and cord to be lowered or well separated from the under side of the work, and positioned in the path of the throat of the open scissors, so that it is not necessary to cause the upper scissors blade point to graze the under surface of the work to pick up the threads and cord to be cut. Also, cord and looper-thread lengths sufficient for the beginning of the next sewing operation are pulled through the throat member 31.

The scissors device comprises the upper blade 144, Fig. 4, which is rigidly carried by the usual lever 145 fulcrumed at 146 on the turret-carrying frame block 147. Pivoted at 148 on the upper blade 144 is the lower blade 149 the tail of which carries a stud pin 150 which is embraced by the forked end of a lever 151 fulcrumed at 152 on an extension 153 of the lever 145. The lever 151 has a follower stud 154 which works in a scissors-opening-and-closing cam-slot 155 in a stationary cam-plate 156 fixed to the bed-frame 4. When the scissors device is in retracted position, Fig. 4, the blades are closed. When the lever 145 is 70

swung to advance the scissors device to cutting position, the blade 149 is opened to admit the thread and cord and then closed. The upper scissors blade 144 is also adjustable about the axis of the fulcrum screw 148 and has a tail which carries the clamp screw 157 passing through the slot 158 in the carrier lever extension 153. This adjustment permits the arcuate path of the advancing point of the upper scissors blade 144 to be nicely set to pass over and seize the cord and looper-thread, as shown in Fig. 19.

The scissors carrier-lever 145 is connected as usual by a link 159 to the forward end of a lever 160 which is fulcrumed at 44 on the bed-frame 1 and has an arm 162 carrying a follower roll 163 entering the actuating cam-slot 164 in the outer face of the gear wheel 48 on the cross rotary shaft 28.

To insure a free run of cord and thread in the needle-throat-tipping operation, means are provided to release the tension on the looper-thread and to supply slack cord.

The looper-thread tension device is shown at 165, Fig. 4. It is a conventional double-disk tension device and there is associated with it a tension-releasing lever 166 carrying the usual wedge 167 adapted to be projected between the tension disks to release the tension. The lever 166 is fulcrumed at 168 on the bed-frame and carries two pins 169 between which extends an arm 170 carried by a rock-shaft 171 which is journaled in and longitudinally of the bed 1. At its rearwardly projecting end the rock-shaft 171 carries an upstanding arm 172, Fig. 2^b, which is engaged by the inclined face 173 of a block 174 fixed to the screw-pin 175 at the lower end of the stop-motion-actuating arm 21. When the stop-motion arm 21, Fig. 2, is swung clockwise to start the sewing operation, the block 174 engages and shifts the arm 172 to rock the shaft 171 in a clockwise direction, Fig. 4; thereby withdrawing the wedge 167 from between the looper-thread-tension disks 165 to restore the normal sewing tension on the looper-thread. When the sewing is completed, the reverse action occurs and the looper-thread tension disks 165 are separated or opened. The spring 176 biases the rock-shaft 171 and lever 166 to tension-releasing position.

The cord c runs from the supply through a guide-tube 177, Figs. 27 and 28, thence through a tension device 178 mounted on the free end of a lever arm 179 which is frictionally fulcrumed at 180 on the outside of the bed 1. From the tension device 178 the cord c runs upwardly and in through the hole 181, Fig. 18; thence over the cord sustaining shank 181' of the spring hook 181" to and through the cord-guiding apertures 32' and 32 in the needle-throat member 31. The cord tension device 178 is moved up and down at appropriate times during a buttonhole producing cycle to give slack cord to the needle-throat member and to slip the tension device 178 on the cord. The tension carrying lever 179 includes a pair of arms 182 and 183. The arm 182 has a straight inner edge 184 terminating in an abrupt drop-off shoulder 185 for cooperation with the pins 186, 186' on the disk 187 fast on the cross rotary shaft 28. The arm 183 has an inner curved edge-portion 188 for co-operation with the pins 180, 181 on the inner face of the disk 187, as will be hereinafter described.

There is mounted on the bracket-arm 3 a needle-thread nipping and pull-off device which is actuated by the clamp-closing lever 64. This de-

vice, Fig. 29, comprises a post 192 having a thread guiding hole 193. Secured to the post 192 slightly above the hole 193 is a collar 194 carrying the fulcrum screw 195 of a nipper-release lever 196 the toe 197 of which is adapted to depress the nipper-head 198 which is slidably mounted on the post 192 and is biased upwardly to nip the thread by the spring 199. Connected to the clamp-closing lever 64 is the rod 200 having at its upper end a lateral extension 201 overlying the needle-thread t and underlying the nipper-release lever 196.

When the clamp-closing lever 64 is depressed to close the work-clamps, the lateral extension 201 of the rod 200 is drawn downwardly from dotted line to full line position, Fig. 29, to first nip the needle-thread t and then pull a measured length of needle-thread from the supply. During the recovery motion of the clamp-closing lever, the pulled-off needle-thread is slackened and the lever 196 is operated to open the nipper 198, 194 and permit the needle-thread t to run freely to the needle.

The needle-thread runs from the supply through the usual tension device 202 and take-up device 203, through the nipper 194, 198 and down through the hollow needle-bar 204 to the needle 5, reference being had to the Spaine application, Serial No. 204,273, filed Apr. 26, 1938, for a more complete description of the course of the needle-thread. The present machine is equipped with the needle-thread tension releaser disclosed in said application Serial No. 204,273, and with the buttonhole cutter safety device disclosed in the Spaine application Serial No. 129,489; filed July 16, 1938.

The scissors actuating lever 160 has integral with it an upwardly and rearwardly inclined arm 205, Figs. 1, 4, 7 and 8, carrying a tripping point 206 formed with a beveled nose 207, Fig. 4. During the scissors-advancing movement of the lever 160, the tripping point 206 on the lever-arm 205 wipes idly past the spring-biased lever-arm 72 of the clamp-release mechanism. During the reverse or scissors-retracting movement of the lever 160, the tripping point 206, moving from dotted line to full-line position, Fig. 7, strikes the lever-arm 72 and rocks the shaft 68 to withdraw the latch 66 from the arm 67 and release the work-clamps. This same movement of the tripping point 206 forces the lower end of lever-arm 72 against the plate 208 carried by the link 87 and shifts the link 87 in a direction to break the toggle 71, 79, 80 and unspread the work-clamp.

Operation

55

At the beginning of a buttonhole producing cycle, when work is introduced to the machine, a loose end of needle-thread is hanging from the eye of the needle and the end of the looper-thread is confined between the hook 185 of the needle-thread cutter and the auxiliary looper or detainer 8. A cord end, preferably not less than $\frac{3}{4}$ inch is projecting from the needle opening 30 in the throat member 31. This cord end leads 65 forwardly under right cord-aligning plate 209, Fig. 23, and projects upwardly through the gap 210 between the cord aligning plates 209, 211 mounted on the lower clamp-plates 56, as shown in Figs. 5 and 6. This cord end is merely positioned by the 70 plates 209, 211; not pinched.

When the machine is started, the clamp-closing lever 64 is given its customary rocking impulse to close the work-clamps and pull needle-thread from the supply. The closing of the nipper 75

194, 198 prior to the pull-off action of the lateral bar 201, prevents unthreading of the needle. On the recovering motion of the clamp-closing lever 64, the pulled off needle-thread is given up for 5 use by the needle in forming the initial stitch. Also, during said recovery motion, the button-hole-cutter starting push-rod 212 swings the gate 213 to initiate the single rotation of the button-hole cutter shaft 129 during which the button-hole 10 cutter levers are advanced and closed to cut the button-hole slit and then retracted. After the button-hole is cut, the cam 213' on the cutter shaft 129 actuates the T-shaped lever 220 to spread the work-clamps. The cam 123 on the 15 cutter shaft then depresses the lever 122 to start the rapid feed of the work-clamps from initial position to sewing position. When the work-clamps reach sewing position the rapid-feed throw-out is tripped by one of the points 117 and 20 the stop-motion lever is tilted to running position by the start-sewing cam 26 on the pattern wheel 27. This action rocks the shaft 171 to restore the looper-thread tension 165.

In sewing down the first side of the buttonhole, 25 after the cord is firmly bound by the initial over-seaming stitches the cord pull-off lever 179, Fig. 1, is moved down by action of the pin 184 on arm 182, Fig. 27, to slip cord through tension 178 and pull cord from the supply. In sewing around the 30 eyelet-end of the buttonhole, the cord pull-off lever 179 is moved from full to dotted line position by the action of the pin 191 on the curved edge 188 of the arm 183, Fig. 27, to give slack cord and prevent distortion of the eyelet-end of 35 the buttonhole. In sewing down the return side of the buttonhole, the cord pull-off lever 179 is moved down to slip cord through tension 178 and pull from supply by the action of the pin 186' on the arm 182, Fig. 28. This pulled off cord is rendered slack before the thread and cord trimming operation occurs, by the action of the pin 190 on the curved edge 188 of the arm 183, Fig. 28.

When the sewing operation is completed, the return of the stop-motion lever 19 to its vertical position releases the looper-thread tension through the mechanism shown in Figs. 2^a and 2^b. The rapid feed is also tripped into operation by the usual stop-motion controlled pawl 126, Fig. 1. During the rapid feed of the work-clamps from sewing position to initial position, the cord pull-off lever 179 is moved from full line to dotted line position, Fig. 28, as above explained, to give slack cord for the thread and cord cutting operation, and avoid jerking and spilling of the cord from the supply spool by the tipping needle-throat member.

Immediately the reverse rotation of the turret 10 starts, the needle-thread cutter 133, 134 is operated, Fig. 15, to cut the work-leg of the last needle-loop, retained by the auxiliary looper 9. The horn 135 of the blade 133 picks up the looper-thread between the looper-eye and the outer edge of the auxiliary looper 9 over which the looper-thread lies. On the recovery motion of the needle-thread cutter, the looper-thread is caught and retained by the horn 135.

Near the finish of the reverse rotation of the turret, the roller 36 on the needle-throat carrying yoke 33 enters the slot 37 in the needle-throat-tipping lever 38 which takes control of 70 the yoke 33 when the latter is unlatched at a slightly later stage by the stationary block 54 over which the follower element 51 rides. Before the follower element 51 drops off of the end 54 of the block 54, the needle-throat tipping lever is

moved slightly by its actuating cam, so that the latch 35' will not re-lock the yoke 33 when released as the turret reaches the end of its reverse rotation.

The needle-throat member is now tipped forwardly to the position shown in Fig. 19 simultaneously with the advance of the scissors device which seizes and cuts the cord and looper-thread about midway between the last stitch in the work and the needle-throat member 31, as 10 shown in Fig. 20. During the advancing and closing movement of the scissors, the tripping point 206 passes the spring-biased lever 12 to get set for the clamp-opening and unspreading 15 operation which takes place during the retraction of the scissors device and the return of the needle-throat member to its vertical position.

The cord alining plate 209 is formed with a forwardly and downwardly inclined tongue 214 having a pointed extremity 215 terminating close 20 to the path of arcuate tipping movement of the needle-throat member 31. As the needle-throat member is being returned to its vertical position, it passes under the point 215 of the tongue 214, which picks up the cord end and guides it into 25 the gap 210, Fig. 23 between the cord alining plates 209, 211, so that the cord end is confined in proper position to be overseamed by the needle 5 in forming the initial stitches of the next buttonhole. The work-clamps are unspread just 30 after the point 215 has picked up the cord end or immediately after the position of the parts shown in Fig. 22.

As the needle-throat member is being restored 35 to its vertical position, after passing the position shown in Fig. 22, it wipes the cord c against the under side of the cord alining plate 209, Fig. 20^a, back of the tongue 214 and, as the cord-supply is slack, pulls some but not all of the available slack cord through the needle-throat member. 40 The cord end is ironed back by this wiping action and alined accurately within the field of lateral vibration of the needle 5. This is a very important consideration in a 'cut-first' machine 45 thread and cord trimmer giving cord ends of sufficient length for the subsequent tacking operation, as the trade demands. The friction of the cord end in moving into the V-shaped gap 210 assists in pulling slack cord through the needle-throat member. The under surface of the 50 plate 209 may also be slightly roughened for this purpose.

The tipping movement of the needle-throat member 31 also drags the looper-thread past the pickup horn 135 on the needle-thread-cutter 55 blade 133 if, for any reason, the looper-thread has not already been picked up by said horn during the needle-thread cutting action of the blade 133. There is enough slack cord available at the beginning of a sewing operation for the 60 sewing of the first $1/4$ " of the buttonhole or until the cord is firmly bound by the overseaming 65 stitches.

The stitched and trimmed buttonhole produced by the machine is shown in Fig. 17. It 65 comprises the body-material 216 having the buttonhole slit 217, the edges of which are covered by the usual overseam 218 made over the cord c, the ends of which cord protrude from the ends of the overseam 218. In practice these protruding cord and thread ends are twisted together or tucked through the end of the button-hole slit prior to presentation of the stitched buttonhole to the usual bar-tacking machine which binds the cord and thread ends at the point 219.

and finishes the end of the buttonhole; any protruding thread and cord ends being then trimmed by hand.

It is to be understood that reference herein to under thread is intended to include either a looper-thread or a stay cord, both of which are under threads leading upwardly through the sewing aperture 30 in the needle-throat member 31 to the work. It is obviously immaterial to the invention, in its broader aspects, whether or not a stay cord is used. If a stay cord is not used, the looper-thread will be drawn through the needle-throat member, the same as the cord, and severed, leaving a thread end long enough for tacking.

The foregoing specification is to be read in an illustrative sense and not in limitation of the invention the scope of which is defined in the appended claims.

Having thus set forth the nature of the invention what we claim herein is:

1. In a buttonhole sewing machine adapted to perform a predetermined sewing operation and then come to rest, the combination with stitch-forming mechanism and work-holding means movable relative to each other during the sewing operation, of a needle-throat member through which an under thread is led to the work, means movable after the sewing operation to move the needle-throat member downwardly and away from the last stitch in the work, thereby drawing a length of under thread through the needle-throat member and separating said drawn out thread length from the work, and means to cut the thread.

2. In a buttonhole sewing machine adapted to perform a predetermined sewing operation and then come to rest, the combination with stitch-forming mechanism and work-holding means movable relative to each other during the sewing operation, of a needle-throat member through which a stay cord is led to the work, means movable after the sewing operation to move the needle-throat member downwardly and away from the last stitch in the work, thereby drawing a length of stay cord through the needle-throat member and separating said drawn out cord length from the work, and means to cut the cord at a distance from the last stitch to afford beginning and finishing cord ends long enough for a subsequent tacking operation, and cord end confining means to position within the field of lateral vibration of the needle the beginning end of the cord protruding from the needle-throat member.

3. In a buttonhole sewing machine, the combination with work-holding means and stitch-forming mechanism, the latter including a needle and under-thread mechanism with a threaded looper, the under-thread mechanism retaining a loop of needle-thread at the end of a sewing operation, the work-holding means and stitch-forming mechanism being relatively movable to sew about a buttonhole, a needle-throat member through which a stay cord and a looper-thread are led to the work, means to cut the last needle-thread loop retained by the under-thread mechanism, means to thereafter move the needle-throat member downwardly and away from the last stitch to pull out lengths of stay cord and looper-thread and separate them from the work, and means to cut the pulled out stay cord and looper-thread between the last stitch and the moved needle-throat member.

4. A buttonhole sewing machine having a frame

including a bed and overhanging bracket-arm, stitch-forming mechanism including a needle and under-thread mechanism, a turret carrying said under-thread mechanism, a work-clamp, a feed-wheel, a needle-throat member pivotally carried by said turret for tipping movements, a cross-rotary shaft journaled in said bed and connected to said feed-wheel, and a cam on said cross rotary shaft and connections for tipping said needle-throat member.

5. A buttonhole sewing machine having a frame including a bed and overhanging bracket-arm, stitch-forming mechanism including a needle and under-thread mechanism, a turret carrying said under-thread mechanism, a work-clamp, a feed-wheel, a needle-throat member pivotally carried by said turret for tipping movements, a cross-rotary shaft journaled in said bed and connected to said feed-wheel, and a cam on said cross rotary shaft and connections for tipping said needle-throat member, a thread cutter and another cam on said cross rotary shaft and connections for operating said thread cutter when said needle-throat member is in a tipped position.

6. In a buttonhole sewing machine, a needle and under-thread mechanism, a rotary turret carrying said under-thread mechanism, needle-thread cutting means carried by said turret, and a stationary block mounted alongside said turret in the path of an element of said needle-thread cutting means, to actuate said means by the rotary motion of said turret.

7. In a buttonhole sewing machine, a needle and under-thread mechanism, a rotary turret carrying said under-thread mechanism, needle-thread cutting means carried by said turret, and a stationary block mounted alongside said turret in the path of an element of said needle-thread cutting means, to actuate said means by the rotary motion of said turret, said means including a needle-thread-cutting blade having a needle-thread cutting edge and an under-thread catching and retaining horn.

8. In a buttonhole sewing machine, stitch-forming mechanism including a needle, a work-clamp, a clamp-closing lever, a stop-motion device for the stitch-forming mechanism, means to cut the needle-thread at the end of a sewing period and allow a free end of needle-thread to hang from the eye of the needle, and a needle-thread nipper and pull-off device connected to be actuated by movement of said clamp-closing lever.

9. In a buttonhole sewing machine, stitch-forming mechanism including a needle and under-thread mechanism, a stop-motion device for the stitch-forming mechanism, a needle-throat member having a sewing aperture, a work-clamp, clamp-closing means, clamp-spreading means, an under thread trimmer occupying a retracted position during a sewing period, a lever and connections to advance the thread trimmer to trimming position, and means actuated by said lever, in the trimmer retracting motion of the latter, to open and unspread the work-clamp.

10. A buttonhole sewing machine having a travelling work-clamp and stitch-forming mechanism including a needle and under-thread mechanism, a stop-motion device for the stitch-forming mechanism, a turret carrying said under-thread mechanism, a needle-throat member carried by said turret, means to move the work-clamp into and out of sewing relation with the stitch-forming mechanism and to sew about a buttonhole, means additional to said travelling

movement of the work-clamp away from sewing position to pull a length of under thread through said needle-throat member at the close of a sewing period, and means to sever said under thread at a point removed from the last stitch in the work a distance greater than the travel of the work-clamp away from sewing position.

11. A buttonhole sewing machine having a travelling work-clamp and stitch-forming mechanism including a needle and under-thread mechanism, a stop-motion device for the stitch-forming mechanism, a turret carrying said under-thread mechanism, a needle-throat member mounted on said turret and having a sewing aperture, means to move the work-clamp from a retracted position into sewing position and return, means to lower the needle-throat member after the work-clamp has been moved out of sewing position, thereby to separate the under thread from the work, and means to sever the under thread.

12. A buttonhole sewing machine having a travelling work-clamp and stitch-forming mechanism including a needle and under-thread mechanism, a stop-motion device for the stitch-forming mechanism, a turret carrying said under-thread mechanism, a needle-throat member mounted on said turret and having a sewing aperture, means to move the work-clamp from a retracted position into sewing position and return, means to move the needle-throat member after the work-clamp has been moved out of sewing position, thereby to pull additional under thread through the needle-throat member and provide cutting space between the under thread and the under side of the work-clamp, and means to sever the under thread.

13. A buttonhole sewing machine having a traveling work-clamp and stitch-forming mechanism including a needle and under-thread mechanism, a stop-motion device for the stitch-forming mechanism, a turret carrying said under-thread mechanism, a needle-throat member mounted on said turret and having a sewing aperture, means to move the work-clamp from a retracted position into sewing position and return, an under thread severing device, means to move said device to thread-severing position in a plane removed from the sewing point in a direction away from the initial position of the work-clamp, and means to shift the needle-throat member so that the sewing aperture thereof crosses said plane prior to the thread-severing operation.

14. In a buttonhole sewing machine, the combination with work-holding means and stitch-forming mechanism including a needle and under-thread mechanism, a turret carrying said under-thread mechanism, a needle-throat member carried by said turret and having a stay-cord-guiding aperture, means to relatively move the work-holding means and stitch-forming mechanism into and out of sewing relation and to sew about a buttonhole, a stay-cord-severing device, means to supply slack stay cord to said needle-throat member immediately prior to the stay-cord-severing operation, and means to pull stay cord through the needle-throat member in the normal direction of travel of the stay cord, after the cord severing operation and prior to the beginning of the next sewing period.

15. A buttonhole sewing machine having, stitch-forming mechanism including a needle and under-thread mechanism including a threaded looper, a stop-motion device for the

stitch-forming mechanism, means to sever the needle-thread, means to sever the looper-thread, and means to loosely confine and position the beginning end of looper-thread, without nipping the latter, during the formation of the initial 5 stitches of an ensuing sewing period.

16. A needle-thread cutting blade for the turret of a buttonhole sewing machine, said blade having at its free end a slot defining long and short horns, said long horn having a knife-edge 10 at said slot and said short horn being curved toward said knife-edge to provide a looper-thread catching hook.

17. In a buttonhole sewing machine, the combination with the under-thread mechanism and 15 a turret carrier therefor, of a tipping needle-throat member mounted on said turret, and stay-cord-severing means movable in a path crossed by the needle-throat member in the tipping movement of the latter.

18. In a buttonhole sewing machine, a rotary turret, a needle-throat support mounted on said turret, a needle-throat member mounted on said support and having a sewing aperture, a latch carried by said turret to lock said support in 25 sewing position, means to move said latch to unlock said support, means to move said support to carry said needle-throat member away from sewing position, an under thread trimmer, and means to move said trimmer across the space 30 vacated by said needle-throat member to trim the under-thread.

19. In a buttonhole sewing machine, stitch-forming mechanism, including a needle, under-thread mechanism, and a needle-throat member through which an under-thread runs to the work, work-holding means, means to relatively move the stitch-forming mechanism and work-holding means into and out of sewing relation and to sew about a buttonhole, the relative movement out of sewing relation drawing under-thread in a given direction out of the needle-throat member, means to move the needle-throat member in the reverse direction to draw an increased length of under-thread through the 45 needle-throat member, and means to sever the under thread between the needle-throat member and the work.

20. In a buttonhole sewing machine having work-holding means and stitch-forming mechanism including a needle and a cord guiding needle-throat member, and under-thread mechanism mounted on a turret, and with means to relatively move the work holding means and stitch-forming mechanism into and out of sewing relation, and with a scissors thread trimmer mounted below the work for movement cross-wise of the direction of length of the buttonhole to cut the under-thread and cord between the needle-throat member and the last stitch in the 55 work, the improvement which consists in mounting the needle-throat member for movement upon and relative to the turret to pull additional under-thread and cord through the needle-throat member, and in shifting the path of travel of the scissors device away from the position of the last stitch in the work to cross the space vacated by movement of the needle-throat member and sever the thread and cord pulled through the latter.

21. In a buttonhole sewing machine, the combination with work-holding means and stitch-forming mechanism including a needle and under-thread mechanism, a turret carrying said under-thread mechanism, a needle-throat mem-

ber carried by said turret and having a stay-cord-guiding aperture, means to relatively move the work-holding means and stitch-forming mechanism into and out of sewing relation and to sew about a buttonhole, a stay-cord-severing device, and means to supply slack stay cord to said needle-throat member prior to the stay-cord-severing operation.

22. A buttonhole sewing machine having work-holding means and stitch-forming mechanism with means to relatively move them to sew about a buttonhole, a needle-throat member through which an under thread runs to the work, a rotary turret carrying said needle-throat member, means to move said member relative to said turret away from the needle-path after a sewing operation is completed to draw out under thread, and means to sever the under thread between said member and the work while said member occupies a position on said turret displaced from the needle-path.

23. A buttonhole sewing machine having work-holding means and stitch-forming mechanism with means to relatively move them into and out of sewing relation and to sew about a buttonhole, a needle-throat member through which an under thread runs to the work, the relative movement of the work-holding means and stitch-forming mechanism out of sewing relation drawing a length of under thread out of the needle-throat member, means to slip the needle-throat member along the under thread in a direction away from the last stitch in the work to augment the length of under thread between the needle-throat member and the last stitch, and means to sever said augmented thread-length.

24. A buttonhole sewing machine having work-holding means and stitch-forming mech-

anism with means to relatively move them into and out of sewing relation and to sew about a buttonhole, a stay-cord-guiding needle-throat member, the relative movement of the work-holding means and stitch-forming mechanism 5 out of sewing relation drawing a length of cord out of the needle-throat member, means to slip the needle-throat member along the cord in a direction away from the last stitch in the work to augment the length of cord between the 10 needle-throat member and the last stitch, and means to sever said augmented cord-length at a point sufficiently distant from both the last stitch and the needle-throat member to provide 15 cord ends long enough to be subsequently bar-tacked in another machine and re-trimmed by hand beyond the bar-tack.

25. A buttonhole sewing machine having a work-clamp and stitch-forming mechanism with means to relatively move them into and out of 20 sewing relation and to sew about a buttonhole, work-clamp closing and opening means, a needle-throat member through which an under thread runs to the work, the relative movement of the closed work-clamp and stitch-forming 25 mechanism out of sewing relation drawing a length of under thread out of the needle-throat member, means operating before the work-clamp is opened to augment the length of under thread between the needle-throat member and the last 30 stitch in the work, and means to sever the augmented under thread length at a point sufficiently distant from both the last stitch and the needle-throat member to provide under thread 35 ends in the work long enough to be bar-tacked in another machine and re-trimmed beyond the bar-tack.

EDWARD P. SPAINE.
HAROLD C. FAULKNER.
